(57) **CLAIM**

The ornamental design for a pinch clamp as shown.

DESCRIPTION

FIG. 1 is a front, top, right perspective view of a pinch clamp showing the new design.

FIG. 2 is a front, top, left perspective view thereof.

FIG. 3 is a front, bottom, left perspective view thereof.

FIG. 4 is a bottom, rear, left perspective view thereof.

FIG. 5 is a left side elevation view thereof.

FIG. 6 is a front elevation view thereof.

FIG. 7 is a rear elevation view thereof,

FIG. 8 is a top plan view thereof; and,

FIG. 9 is a bottom plan view thereof.

1 Claim, 9 Drawing Sheets
